UNITED STATES PATENT OFFICE

91,859

DESIGN FOR A VEHICLE TIRE

Henry Brett, Cumberland, Md., assignor to The Kelly-Springfield Tire Company, Cumberland, Md., a corporation of New Jersey

Application May 13, 1933, Serial No. 48,103

Term of patent 14 years

To all whom it may concern:

Be it known that I, HENRY BRETT, a citizen of the United States, residing at Cumberland, in the county of Allegany and State of Maryland, have invented a new, original, and ornamental Design for a Vehicle Tire, of which the following is a specification, reference being had to the accompanying drawing, forming a part hereof:

Figure I is a perspective view of a fragment of the tire showing the design.

Figure II is a transverse cross-sectional view through the tire of Figure I.

Fig. III is a perspective view of a portion of a pneumatic tire having a tread design embodying the present invention.

I claim:

The ornamental design for a vehicle tire as shown.

HENRY BRETT.
